UNITED STATES PATENT OFFICE.

LELAND V. COCKRUM, OF KNOX CITY, MISSOURI.

SOLDERING AND BRAZING APPARATUS.

No. 838,168.

Specification of Letters Patent.

Patented Dec. 11, 1906.

Application filed March 20, 1906. Serial No. 307,097.

To all whom it may concern:

Be it known that I, LELAND V. COCKRUM, a citizen of the United States, residing at Knox City, in the county of Knox and State of Missouri, have invented certain new and useful 5 Improvements in Soldering and Brazing Apparatus, of which the following is a specification.

This invention has for its object to devise 10 simple mechanism for utilizing alcohol, naphtha, or like volatile hydrocarbon in the industrial arts for soldering, brazing, welding, and like operations requiring the concentration of a flame upon the work.

15 As generally practiced an alcohol or spirit lamp has its flame diverted by means of a blowpipe upon the work.

The present invention aims to obviate the blast created by the operator blowing 20 through a tube, this being accomplished by generating a vapor in a tank or closed receptacle by the application of heat thereto, said vapor being directed through a tube and blowpipe under pressure sufficient to create 25 a jet, such as formed in the ordinary way.

For a full description of the invention and the merits thereof and also to acquire a knowledge of the details of construction of the means for effecting the result reference 30 is to be had to the following description and accompanying drawings.

While the invention may be adapted to different forms and conditions by changes in the structure and minor details without de- 35 parting from the spirit or essential features thereof, still the preferred embodiment is shown in the accompanying drawings, in which—

Figure 1 is a perspective view of an apparatus embodying the invention. Fig. 2 is a 40 sectional view of the tank or generating-receptacle, showing the flexible tubing replaced by means of a burner.

The tank or generating-receptacle 1 is 45 preferably of flattened form in order to provide an extended surface for the action of a heater, such as a lamp 2, and at the same time providing a comparatively small space for the reception of a quantity of alcohol, 50 naphtha, or like volatile hydrocarbon. The tank or generator 1 is supported by means of a frame or stand 3, which in the preferable construction is closed, so as to form a housing to prevent escape of the heat and to con- 55 fine the same for a greater length of time.

The heater 2 may be a lamp of any kind and adapted to receive wood-alcohol or like burning fluid. This lamp is arranged below the generator in position to direct the heat produced by the flame upon the bottom of 60 said generator to the best possible advantage. The tank or generator is of flattened form and circular outline and is provided with a filling-opening 4, closed by means of a screw-cap or in any preferred way. A tube 65 5 rises from the top of the generator and is centrally disposed and is adapted to receive either a burner 6 or a flexible tube 7, the latter having a blowpipe 8 fitted to its outer end. A support 9 is removably fitted to the 70 tank and is forked at its upper end, as indicated at 10, to receive the tube 7 and hold the same away from the tank, so as to obviate injury thereto, which would result if permitted to come in contact with the generator when the latter is heated. The support 9 is stepped in a socket 11, fitted to the top of the generator, and provided in a side with a set-screw 12 for securing the support when placed in position. 80

To use the apparatus, a quantity of wood-alcohol or like burning fluid of a volatile nature is placed in the tank 1 through the opening 4, and heat is applied to the tank by means of the lamp 2, whereby the alcohol or 85 like volatile fluid in the tank is converted into vapor and passes off through the tube 5 and may be consumed at the burner 6 or at the end of the blowpipe 8. By regulating the vapor of the lamp the quantity of vapor 90 generated in a given time may be varied. Hence the jet at the end of the blowpipe may be regulated to suit the character of work. When it is not required to use the apparatus and the tank contains a quantity of burning 95 fluid, the tube 5 may be closed by a cap or plug, so as to prevent the waste of the fluid by evaporation, as will be readily comprehended. The support 9, as well as the tube 7, has detachable connection with the tank or 100 generator. Hence it is possible to store the apparatus in a comparatively small space.

Having thus described the invention, what is claimed as new is—

1. In apparatus of the character set forth, 105 a generating - tank of flattened form and of considerable diametrical extent, and provided with a tube and a socket, a lamp for heating the generator, a flexible tubing provided with a blowpipe and adapted to make 110

connection with the tube of the generator, and a support fitted in said socket and having a fork to receive the flexible tube.

2. The herein-described soldering or brazing apparatus, the same comprising a stand, a shallow generator fitted to the upper end of the stand and provided with a tube and a socket, a lamp adapted to be supported by the stand at a point beneath the generator, a flexible tube connected to the tube of the

generator and connected at its outer end to the blowpipe, and a support detachably fitted to the socket of the generator and having a fork to receive the flexible tube.

In testimony whereof I affix my signature 15 in presence of two witnesses.
